UNITED STATES PATENT OFFICE.

FELIX TONNAR, OF DÜLKEN, GERMANY.

SHEDDING MECHANISM FOR LOOMS.

SPECIFICATION forming part of Letters Patent No. 445,098, dated January 20, 1891.

Application filed September 25, 1889. Serial No. 325,005. (No model.) Patented in England August 30, 1889, No. 13,728.

To all whom it may concern:

Be it known that I, FELIX TONNAR, of the city of Dülken, in the Kingdom of Prussia and German Empire, have invented certain new and useful Improvements in Shedding Mechanisms for Looms, (for which I have obtained Letters Patent in Great Britain, No. 13,728, dated August 30, 1889,) of which the following is a specification, reference being had therein to accompanying drawings.

This invention relates to new and useful improvements in shedding mechanism for looms; and it consists in certain details of construction hereinafter described and claimed, reference being had to the accompanying drawings, in which—

Figure 1 is a longitudinal section of my improved shedding mechanism for looms. Fig. 2 is a section on the line $x x$ of Fig. 1. Fig. 3 is a plan of the same. Fig. 4 is a detail, partly in section. Fig. 5 shows a modification, and Fig. 6 the general arrangement of my improved shedding mechanism.

The frame consists of two side parts A, connected by cross-bars B.

a' is a bar on which the angle-levers a are fulcrumed, the latter being connected with the harness-shafts M above and below by means of strings a^2 , Fig. 6.

b are arms movably fastened to the angle-levers a at a^3 and connecting the same with the actuating mechanism in such a way as to receive from the latter a reciprocating movement and impart a corresponding movement to the shafts for forming the shed. The said arms b are each provided with a pin b' , which loosely engages with the side surface of one of the cog-wheels c , journaled on pins d' of the levers d , the said levers being fulcrumed at d^2 . Each said lever d is also provided with a pin d^3 , resting in a semicircular slot c' , formed in the cog-wheel c for the purpose of limiting the rotary movement of the latter.

k^3 is a frame arranged below the levers d , capable of being lifted and lowered by means of an eccentric t^3 , Fig. 2, mounted on the axis h^2 of a toothed cylinder g . A number of angular catches o^3 are fulcrumed to a bar m^3 on the said frame k^3 in such a manner as to lean against a cross-piece n^3 , Fig. 3, on the same. s^3 is a second frame carrying a hexagonal

pattern-cylinder p^3 , capable of being lifted and lowered by the eccentric t^3 , also mounted on the axis h^2 , an arm p^4 of the said frame s^3 resting on the said eccentric t^3 . The cards of the pattern-chain q^3 , hanging on the pattern-cylinder p^3 , are either provided with a hole or blank. If the pattern-card appearing below the horizontal arm of one of the angular catches from below, after a turn of the pattern-card, be a blank—that is to say, without a hole—then the horizontal arm of the angular catch will be raised by means of one of the pins o^4 , provided with a head and loosely sliding in a projecting portion o^5 , formed on the frame k^3 , thus causing the respective vertical arm of the said angular catch to be brought under a shoulder r^3 of the corresponding lever d upon the frame k^3 , and the lever d now being raised by the eccentric t^3 the cog-wheel c is likewise raised and made to engage with a toothed cylinder f arranged above it and continuously rotating, the said cog-wheel being kept in position for engagement with the said toothed cylinder as long as required by the eccentric t^3 . The frame s^3 and the pattern-cylinder p^3 , actuated by the eccentric t^3 thereupon, being lowered, one of the pegs u^3 on the pattern-cylinder is caught by a hook v^3 of a pawl w^3 , causing the pattern-cylinder to be rotated to the extent of one-sixth of its circumference, thereby bringing a new card on the upper surface of the said pattern-cylinder. Supposing that the card now brought to the top have a hole, then the cog-wheel c is permitted to engage with the toothed cylinder g , arranged below it on the axis h^2 and rotating in an opposite direction to that of the other toothed cylinder f . By drawing the fork w^3 to the right or left by means of a string the pattern-cylinder may be caused to rotate to the right or left, as the case may be.

In the modified arrangement shown in Fig. 5 the forked pawl w^3 is actuated by two cam-wheels z and z' , mounted on the axis of the toothed cylinder f , the said pawl being fulcrumed at x^2 and forked at its other end, and each of the ends $x x'$ being provided with a roller. The end x engages with the cam-wheel z or the other end x' engages with the cam-wheel z' , as may be desired, the said cam-wheels being so constructed as to cause either

the one or the other of the hooks v^3 of the pawl w^3 to come in contact with a peg u^3 of the pattern-cylinder p^3 , thereby rotating the latter when the same is to come into action. 5 A spring w^4 is applied either at x' or at v^3 , this depending upon the direction in which the pattern-cylinder is to be rotated. The spring w^4 is shown in Fig. 5 as applied at v^3 , thereby bringing the end x' into operation on 10 the cam z' and causing an intermittent movement of the pattern-cylinder p^3 in the direction of the arrow. Both hooks v^3 will pass the pegs u^3 , when the arms x and x' engage with the non-depressed portion of the cams, 15 which occurs when the pattern-cylinder p^3 is in its upward movement, thus preventing the hooks v^3 from interfering. If it is desired to rotate the pattern-cylinder in the opposite direction to that indicated by the 20 arrow, the spring w^4 should be applied to arm x' .

The toothed cylinders f and g are rotated in opposite directions from the conical wheels i' i^3 of a shaft i , each revolution of the said 25 conical wheels corresponding to a revolution of the loom. The number of teeth on either of the said cylinders f and g , however, being but half that of the number on the intermediate cog-wheel c , the latter can only make half 30 a revolution to each revolution of the said toothed cylinders. Thus when the angle-lever a is to be moved, say, to the position indicated at a^x one of the angular catches o^3 must be brought under the lever d , in order 35 to bring the cog-wheel c to engage with the toothed cylinder f , rotating in the direction opposite to the hands of a clock. On the other hand, when the angle-lever a is to be moved the other way it will be necessary that 40 none of the angular catches come below the lever d , so as to allow the cog-wheel c to engage with the toothed cylinder g , rotating in an opposite direction. The extent of the free space or toothless portion to be left or the 45 diameter of the toothed cylinders f and g depends upon the speed at which the shafts are to form the shed. In order to secure a slow movement of the shafts, the free space, and hence also the diameter of the toothed cylinders, will have to be as small as possible, the 50 number of teeth of the said cylinders always being half that of the number on the cog-wheel c .

For the purpose of setting the angle-levers 55 a and the shafts at rest for several shots of the loom when at the end of their movement, or, in other words, permitting the shafts to remain in position at the end of their upward or downward movements, the loom 60 meanwhile making several picks, the wheels c have certain teeth omitted at opposite points on the peripheries thereof to permit the said wheels to run out of mesh with the cylinders f g after moving to the necessary extent to 65 raise or lower the shafts. The cog-wheels c and the levers d are held in their highest as

well as in their lowest position by catches h striking against shoulders of the said levers d , the said catches h being drawn by a spring h' and released by means of an eccentric h^4 70 and lever h^3 . As soon as the levers d or the cog-wheels c are raised or lowered the catch h is disengaged through the eccentric h^4 .

Below the levers d a slide k , Fig. 4, may be 75 preferably arranged for bringing the said levers d from their lowest position into their uppermost position by drawing the said slide k outward. By this means the same result may be obtained as by means of a pattern-chain. On rotating the loom to the extent of 80 one shot at this position of the machine all the shafts of the lower shed will be lifted, the position of the shafts thus obtained being the most favorable one for drawing in the warp. In order to allow of performing this manipulation without requiring to rotate the loom at 85 all, I arrange a coupling i^3 , Fig. 6, on the shaft i by means of which the machine may be uncoupled from the loom. Thus when rearranging the weft the machine may be simply 90 driven by hand by turning the crank g' , Fig. 2, arranged on the side of the lower toothed cylinder g , and the shafts may thus be moved.

In rearranging the weft and taking out 95 weft-threads the pattern-cylinder must be rotated in an opposite direction, this being effected by reversing the pawl w^3 .

Having thusfullydescribed and ascertained the nature of my invention and the manner in which the same is to be performed, what I 100 claim is—

1. In a loom, the combination of a series of vertically-movable gear-wheels, the constantly-revolving toothed cylinders, one of which is mounted above and the other below said 105 gears, a series of levers for carrying said gears, a pattern-cylinder, a series of catches actuated by the pattern-cylinder to engage the gear-carrying levers, a series of pins acting on said catches, a series of arms carrying pins to engage the gears, a series of angle-levers actuated by said arms, the frames k^3 s^3 , and mechanism for actuating said frames, substantially as described.

2. In a loom, the combination of the constantly-revolving toothed cylinders, a series of vertically-movable gear-wheels intermediate 115 said cylinders, a series of levers for carrying said gear-wheels, a pattern-cylinder, a vertically-movable frame s^3 for carrying the pattern-cylinder, the frame k^3 , means for actuating said frames, and a series of catches actuated by the pattern-cylinder to engage the gear-carrying levers, substantially as described.

3. In a loom, the combination of a series of levers, gear-wheels carried thereby, constantly-revolving cylinders, one mounted above and the other below said gears, a cam-operated pattern-cylinder, a cam-operated lifting-frame, and catches on said lifting-frame operated by said pattern-cylinder to engage with 120 125 130

the levers and bring the gears into engagement with either of the cylinders, substantially as described.

4. In a loom, the combination of a series of levers, a series of mutilated gears carried thereby, the constantly-revolving toothed cylinders, one of which is mounted above and the other below said gears, a series of arms carrying pins adapted to engage the gears, a series of angle-levers actuated by said arms, a pattern-cylinder, the frames $l^3 s^3$, means for actuating said frames, and a series of catches carried by one of said frames and actuated by the pattern-cylinder to engage the gear-carrying levers, substantially as described.

5. In a loom, the combination of a series of levers, gears carried thereby, cylinders above

and below said gears, a vertically-moving frame, a pattern-cylinder carried thereby, a series of catches actuated by the pattern-cylinder to engage the levers, a cam-operated frame carrying said catches, a series of pins acting on said catches, a pawl adapted to operate the cylinder, a series of arms carrying pins adapted to engage the said gears, and a series of angle-levers actuated by said arms, substantially as described.

In testimony whereof I have signed my name to this specification in the presence of two subscribing witnesses.

FELIX TONNAR.
